UNITED STATES PATENT OFFICE.

GEORGE R. KURRIE, OF PHILADELPHIA, PENNSYLVANIA.

COMBINED CAP AND GIRDER-SUPPORT.

SPECIFICATION forming part of Letters Patent No. 609,441, dated August 23, 1898.

Application filed March 26, 1898. Serial No. 675,261. (No model.)

To all whom it may concern.

Be it known that I, GEORGE R. KURRIE, a citizen of the United States, residing at Philadelphia, in the county of Philadelphia and State of Pennsylvania, have invented certain new and useful Improvements in a Combined Cap and Girder-Support, of which the following is a specification, reference being had therein to the accompanying drawings.

10 My invention relates to metal caps and base-plates for the wooden columns used in the construction of large buildings that are designed to carry heavy weights upon the floors; and the object of my improvement is to construct a combined cap and girder-support that will be light and strong and always have solid and substantial bearings for the ends of the columns and girders.

In the accompanying drawings, Figure 1 is 20 a side elevation of my improved cap and girder-support, showing the upright columns and the girders fitted therein. Fig. 2 is a vertical sectional view, as on line $y y$ of Fig. 1. Fig. 3 is a plan view of the top of the cap removed from the post. Fig. 4 is a vertical sectional view, as on line $x x$ of Fig. 1, showing the top of the post sawed off out of true or not in a plane at right angles to the side of the column, as many times occurs in such 30 work.

A represents my improved cap and girder-support, which is preferably made of steel and rolled to the shape shown in Figs. 2 and 4. $a a$ are outwardly-beveled flanges forming the sides of the cap and joined together by the intervening flat web portion a' .

B and B' are two upright wooden columns, one fitting underneath and the other on the top of the cap. 40 C C are girders supported horizontally in the ends of the cap that project beyond the posts B B'.

D D are angle-pieces fastened on the under side of the cap A by means of the bolts b.

45 b' b' are holes for the lag-screws that secure the angle-pieces D to the sides of the post. The angle-pieces are placed at these points for the purpose of strengthening the girder-support, and they are made somewhat shorter 50 than the distance between the beveled flanges $a a$, so as to allow a free circulation of air

around the top of the post. By this construction I prevent any accumulation of dampness around the top of the post and provide for a ready and thorough inspection of the top of 55 the wooden column at any and all times. The flanged sides of the cap being beveled both the posts and the girders will always have a solid bearing, no matter whether they are sawed off true or carelessly left out of 60 line in the manner shown in Fig. 4. Should the end of the post or the bottom of the girder not rest squarely upon the flat web portion a' of the cap, the beveled sides of the flanges $a a$ will take the strain and bear against the 65 beveled sides of the posts or girders.

As the ends of the post and girders are forced against the beveled sides of the cap they are held securely in position, and any additional weight placed on the floors will 70 have a tendency to wedge these parts more tightly together. The heads of the bolts $b' b'$ may be made any desired shape, and when the bottom of the girder is cut to fit them they will materially assist in retaining the girders 75 in place.

Instead of having the beveled flanges $a a$ extend both above and below the middle web portion a' , they may be made to extend only on one side of the web portion, if desired; 80 but the best results and the strongest construction is obtained when the beveled flanges $a a$ extend both above and below the web portion, in the manner shown.

Having thus described my invention, what 85 I claim as new, and desire to secure by Letters Patent of the United States, is—

1. A combined cap and girder-support having the two sides that extend parallel with the girder, formed with outwardly-extending 90 flanges that will permit the post to have a wedge-shaped bearing therein, substantially as shown and for the purpose described.

2. A combined cap and girder-support, composed of the outwardly-beveled flanged sides 95 $a a$, joined together by the intervening flat web portion a' , that extends beyond the line of the posts and parallel with the girder, substantially as shown.

3. A combined cap and girder-support, composed of the outwardly-beveled flanged sides 100 $a a$, and the intervening web portion a' , both

of the beveled flanged sides a, a , extending above and below the intervening web portion, substantially as shown.

4. A combined cap and girder-support, composed of the outwardly-beveled flanged sides a, a , the intervening flat web portion a' , and an angle-piece D, secured to the under side of the web portion of the cap and adapted to rest against the side of the wooden column, substantially as shown and for the purpose described.

5. In a cap and girder-support, the combi-

nation of the beveled flanged sides a, a , joined together by an intervening flat web portion with an angle-piece D, secured to the under side of the web portion and made shorter than the distance between the two beveled sides a, a , substantially as shown.

In testimony whereof I affix my signature in presence of two witnesses.

GEORGE R. KURRIE.
